COMBINATION CHEWING GUM AND COIN DISPENSER

James W. Ament, Youngstown, Ohio

Application June 27, 1949, Serial No. 3,574

Term of patent 14 years

(Cl. D52—2)

To all whom it may concern:

Be it known that I, James W. Ament, a citizen of the United States, residing at Youngstown, in the county of Mahoning and State of Ohio, have invented a new, original, and ornamental Design for a Combination Chewing Gum and Coin Dispenser, of which the following is a specification, reference being had to the accompanying drawing, forming a part thereof.

Figure 1 is a perspective view of a combination chewing gum and coin dispenser showing my new design.

Figure 2 is a perspective view of the combination chewing gum and coin dispenser showing the other side.

The broken line representations of the coins and chewing gum are for illustrative purposes only.

I claim:

The ornamental design for a combination chewing gum and coin dispenser, as shown and described.

JAMES W. AMENT.
